United States Patent Office

Des. 178,878
Patented Oct. 2, 1956

178,878

BUILDING

Willard L. Groene, Scottsdale, Ariz.

Application February 13, 1956, Serial No. 40,128

Term of patent 14 years

(Cl. D13—1)

Fig. 1 is a front elevation of a building incorporating my new design.

Fig. 2 is a rear elevation of the building shown in Fig. 1.

Fig. 3 is a left end elevation of the building shown in Fig. 1.

Fig. 4 is a right end elevation of the building shown in Fig. 1.

I claim:

The ornamental design for a building, as shown.
